[57] **CLAIM**

The ornamental design for a shield for protecting a truck driving light from road damage, as shown and described.

DESCRIPTION

FIG. 1 is a perspective view of the shield for protecting a truck driving light from road damage showing my new design, taken from the rear of the shield; FIG. 2 is a rear elevational view thereof; FIG. 3 is a front elevational view thereof; FIG. 4 is a right side elevational view thereof; FIG. 5 is a left side elevational view thereof; and FIG. 6 is a bottom plan view thereof, with both the bottom and top views being identical.

FIG. 2

FIG. 3
